UNITED STATES PATENT OFFICE.

WILLIAM H. DEWAR, OF PHILADELPHIA, PENNSYLVANIA, ASSIGNOR TO POOLEY FURNITURE COMPANY, INC., OF PHILADELPHIA, PENNSYLVANIA, A CORPORATION OF PENNSYLVANIA.

DESIGN FOR A RADIOCABINET.

Application filed May 22, 1924. Serial No. 9,686. Term of patent 7 years.

To all whom it may concern:

Be it known that I, WILLIAM H. DEWAR, a citizen of the United States, residing in Philadelphia, county of Philadelphia, State of Pennsylvania, have invented a new, original, and ornamental Design for Radiocabinet, of which the following is a specification, reference being had to the accompanying drawing, which forms a part thereof.

The figure is a perspective view of a radio cabinet, embodying my design, closed.

I claim—

The ornamental design for a radiocabinet as shown.

WILLIAM H. DEWAR.

Witnesses:

H. J. QUIRK,
M. CAUFFEN.
